INVENTOR

UNITED STATES PATENT OFFICE

98,020

DESIGN FOR A DRESS

Ralph B. Spiro, New York, N. Y.

Application November 23, 1935, Serial No. 59,711

Term of patent 3½ years

To all whom it may concern:

Be it known that I, Ralph B. Spiro, a citizen of the United States of America, residing in Manhattan, county of New York, and State of New York, have invented a new, original, and ornamental Design for a Dress, of which the following is a specification, reference being had to the accompanying drawing, forming part thereof, wherein,

The cross sectional lines on the waist portion of the dress represent shirring.

The vertical lines on the skirt portion of the dress represent gathering.

I claim:

The ornamental design for a dress, substantially as shown, and described.

RALPH B. SPIRO.
